UNITED STATES PATENT OFFICE.

SAMUEL C. MCKEOWN, OF NEWARK, NEW JERSEY, ASSIGNOR TO SPLITDORF ELECTRICAL COMPANY, OF NEWARK, NEW JERSEY.

RESETTING DEVICE.

Application filed December 21, 1920. Serial No. 432,312.

To all whom it may concern:

Be it known that I, SAMUEL C. MCKEOWN, a citizen of the United States, residing at Newark, in the county of Essex, State of 5 New Jersey, have invented certain new and useful Improvements in Resetting Devices, of which the following is a description, reference being had to the accompanying drawing and to the figures of reference marked 10 thereon.

In starting internal combustion engines wherein dynamo or magneto electric machines are employed to furnish the spark to ignite the charges within the cylinders, 15 so called impulse couplings are employed so as to cause the electric machine to periodically rotate at a high speed of rotation irrespective of the speed of rotation of and in timed relationship with the engine shaft. 20 To couple the engine shaft to the shaft of the electric machine two resiliently coupled movable members and a latch dog to temporarily restrain one of them are provided and the dog is automatically thrown out of 25 operation when the speed of the engine shaft is sufficiently high.

The object of this invention is to provide means whereby this dog may be reset into coupling member engaging position.

Another object is to provide means, in devices of this character, to enable the dog to be reset either from the driver's seat or from the front of the engine.

A still further object is to so form the 35 device as to make it equally adaptable to right and left hand rotation of the shaft.

Other objects of this invention will appear after reading this specification in connection with the accompanying drawings 40 in which—

Figure 1 is a view of my resetting device as applied on a coupling plate.

Figure 2 is a top view of the resetting device while

Figure 3 is a similar view showing the parts thereof in their operated position.

Figure 4 is a fragmentary bottom view of my invention.

Figure 5 is a top view of a modified form 50 of my invention, and

Figure 6 is a side view of the device shown in Figure 5.

The invention is directed to a manually 55 actuated train of devices for resetting or shifting the latching devices of an impulse,

coupler to operative position. The impulse coupler to which my invention is preferably applied is of the type shown in the patent to Hermann No. 1,318,206, granted October 7, 1919, and which includes briefly a magneto or dynamo electric machine of any suitable character on which is mounted a plate 1 by means of screws 2. Extending through this plate is a main shaft 3 upon which is rigidly secured the coupling members 4 and 5 of the impulse coupler. Cooperating with the impulse coupler is a latch dog 6 which is pivoted on a stud 7 mounted on the plate 1, and said dog is spring pressed to its normal operative position by means of a spring 8 surrounding a rod 9 passing through a lug 10, said spring bearing at one end against the lug and at the other end against the knee of a toggle joint formed by the rod and one arm 11 of a bell crank lever, the other end of said bell crank lever constituting the latching dog 6. A pin 12 acts as an abutment for the latching devices when thrown to inoperative position, and the latching dog is held in this inoperative position by means 70 of the spring 8. It is likewise held in operative position by said spring. All the above parts are shown and described in the patent to Hermann, and have been referred to here purely for illustrating one embodiment of an impulse coupler to which my invention may be applied. In said patent, there is disclosed automatic means for throwing these latching devices into operative position. The present invention is directed to a manually controlled means 75 designed to be used in place of this automatic means in this particular type of impulse coupler. My improved manually actuated means is normally disconnected from the 80 latching devices so as not to in any way interfere with the automatic throwing out of the latching devices in the manner set forth in said patent. The normal position of the generator is with its shaft parallel 85 with the shaft of the engine. The latching dog swings in a plane at right angles to the axis of the generator. My manually operated device for throwing the latch into operative position is preferably of such type 90 that a pull or a push thereon from the operator's seat or from the front of the engine, and which is in a direction substantially 95 parallel with the generator shaft, will readily shift the latching dog to operative posi- 100 105 110

tion. Automatic means is also provided for restoring the manually controlled devices to normal position when released so that they will not in any way interfere with the throwing out of the latching devices.

Referring more in detail to the drawings, my improved manually controlled operating means for the latching devices is indicated as a whole as at 16.

10 This device comprises a positioning member 17 provided with fingers 18 and 19 adapted to engage the plate on opposite faces thereof adjacent the lug 10 through which the rod 9 passes and a securing stud 20 is adapted to pass through the other lug 13 on the plate. The member 17 is retained in place securely by means of lock nuts 21 screw threaded onto the stud 20 and by means of the fingers 18 and 19 hereinbefore described. The member 17, as in fact is the whole device, is symmetrical with respect to its longitudinal axis and is provided with an additional pair of fingers 22 and 23 for engagement with the plate when the dog and resetting device are mounted for opposite (counterclockwise) rotation of the shaft.

Pivottally mounted on the positioning member 17 about a grooved portion of the stud 20 is an actuating lever 24 provided with two prongs 25 and 26 adapted to slidably engage two similar prongs 27 and 28 of a longitudinally movable tripping member 29 provided with a rod engaging edge 30. A spring 31 sprung between the stud 20 and a lug 32 struck up from the tripping member serves to restore the parts to the position shown in Figures 1 and 2. Both the lower member 17 and the tripping member 29 are channeled as at 33 and 34 and each are provided with struck up ears 35 and 36 respectively to guide the member 29 in its longitudinal movement. The channels are enlarged at 37 and 38 to permit ready assembly of the parts. The lever 24 is also provided with a means for enabling assembly thereof with the member 17, these means comprising a channel 39 terminating in a perforation 40. The lever 24 is provided with a perforation 41 at its free end 45 for attachment thereto of a cable leading either to the driver's seat or to the front of the engine or both. It can be readily seen that a pull in either direction will cause the member 29 to move longitudinally to trip the dog 6 to latching position.

In the modified form of my invention, there are but two members. One of these is a positioning member 42 provided with pairs of fingers 43 and 44 for a purpose similar to the fingers 18, 19, 22 and 23 already described and, a slot 45 encompasses the rod 9. Cooperating with this member, in spring pressed relationship therewith, is the member 46 provided with two cam surfaces 47 adapted to engage and reset the

dog upon movement of the member 46 in either direction. Attached to and preferably integral with the member 46 is the actuating handle 53. To restore the members to normal position after the upper member has been shifted, the member 46 is kerfed as at 48, a corresponding bead 49 is formed on the other member and a compressed spring 50 wound about a stud 51 presses the beaded portions into the kerfed portions thus tending to align the parts. The stud 51 is adapted to pass through the lug 13 or 10 as the case may be and the whole device is adapted to be retained in place on the plate 1 with the spring 50 under tension by means of a nut 52 screw threaded onto the stud.

From the above it will be apparent that I have provided manually controlled actuating means for shifting the latching dog to operative position relative to the coupling members of the impulse coupler. This manually controlled actuating means may be operated by either a pull or a push in a direction substantially at right angles to the line of movement of the latching dog, and is therefore readily actuated from the operator's seat of an automobile or from in front of the engine. The manually controlled means is automatically returned to its normal position when released, and as it is disconnected from the latching devices, the return movement does not in any way affect the position of the latching devices or prevent the throwing out of the latching devices when the speed of the engine reaches a predetermined point.

It is obvious that many of the details of construction and the arrangement of the parts may be varied without departing from the spirit of the invention as set forth in the appended claims.

Having thus described my invention, what I claim is:

1. A resetting device comprising a positioning member, a stud adjacent one end of the positioning member to securely attach the resetting device to a support, prongs on the positioning member at the opposite end thereof adapted to embrace the support, a tripping member on the positioning member, means thereon adapted to engage and push a member and means to move the tripping member.

2. A resetting device comprising an immovable positioning member, a tripping member mounted on the top side of said positioning member slidably longitudinally thereon, said positioning member and tripping member being provided with cooperating guides and slots, said tripping member provided with a part pivoted on said positioning member operable upon movement thereof in one of several directions to engage and move the tripping member and a separately mounted member independent of

all of the previously mentioned members actuated by said tripping member.

3. In resetting mechanism of the class described, latching devices therefor normally held in inoperative position, manually actuated means for shifting the latching devices to operative position, means for automatically returning said actuating means to normal position when released, said manually actuated means being disconnected from said latching devices when said latching devices are in operative position.

4. In resetting mechanism of the class described, latching devices therefor normally held in inoperative position, manually actuated means normally positioned so as to permit free movement of the latching devices, and means actuated by said manual means when shifted laterally to either side of the normal position for shifting the latching devices to operative position.

5. In resetting mechanism of the class described, latching devices therefor normally held in inoperative position, a pivoted manually actuated lever normally positioned so

as to permit free movement of the latching devices, and means actuated by said lever for shifting said latching devices to operative position.

6. In resetting mechanism of the class described, latching devices therefor normally held in inoperative position, a pivoted manually actuated lever normally positioned so as to permit free movement of the latching devices, and means actuated by said lever when moved in either direction for shifting the latching devices to operative position.

7. In resetting mechanism of the class described, latching devices therefor normally held in inoperative position, a pivoted lever, devices operated thereby when said lever is moved in either direction for shifting the latching devices to operative position, means for automatically returning said lever to normal position when released, said manually actuated means being disconnected from said latching devices when said latching devices are in operative position.

In testimony whereof, I affix my signature.

SAMUEL C. McKEOWN.
